C. L. GOODRUM

TELEPHONE EXCHANGE SYSTEM

Filed April 17, 1920

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 17, 1920. Serial No. 374,534.

To all whom it may concern:

Be it known that I, CHARLES L. GOODRUM, a citizen of the United States, residing at New York, in the county of New York, State of New York, have invented certain new and useful Improvements in Telephone-Exchange Systems, of which the following is a full, clear, concise, and exact description.

This invention relates to improvements in telephone exchange systems, and has particular reference to systems employing machine switching in the completion of connections.

There have heretofore been provided in such systems, selector switches which might be directly operated to associate an incoming line with one of a plurality of groups of outgoing lines, thereafter operating in a hunting movement to connect said incoming line to an idle line in the selected group. It has also been proposed to divide such groups of outgoing lines into sub-groups of equivalent trunks, means, such as a group contact, being provided to test the idle or busy condition of each sub-group in a single operation. With such an arrangement, if all the lines in the first sub-group were busy the incoming line would be successively associated with other sub-groups until a sub-group which contained an idle line was found, whereupon the lines in this sub-group would be tested and the incoming line connected to the first idle line encountered. It is obvious that even by subdividing the outgoing lines into equivalent sub-groups, there would still be a loss of time in establishing a connection while busy sub-groups were being tested.

An object of the present invention is to avoid the delay occasioned in testing terminals of groups in which all trunks are busy by preselecting a group containing an idle trunk and causing the selector to immediately hunt in said group.

A preferred embodiment of the invention is shown in the accompanying drawing wherein Fig. 1 partially illustrates diagrammatically two selectors and the circuits for operating one of them; Fig. 2 is an enlarged sectional detailed view of the brush tripping mechanism employed; and Fig. 3 is a similar view taken at right angles to Fig. 2.

In carrying out the invention each selector has its terminal bank divided into groups G, G', etc., to the terminals of which are

connected the trunks to which said selector has access. Each group of terminals is divided into a plurality of rows or subgroups equal in number to the largest digit employed to operate said selector to select an idle trunk. Likewise, the trunks in the various main groups are divided into sub-groups of equivalent trunks and, as will appear in the course of the description, as long as there is an idle trunk in a subgroup of equivalent trunks in group G, the selector will operate to select said idle trunk. When all the equivalent trunks of a subgroup are busy, the selection of an idle trunk is switched to the next main group containing a subgroup in which an equivalent trunk is idle. Each subgroup is shown as comprising ten sets of trunk terminals to which an equal number of trunks are connected. In order to avoid confusion, the drawing illustrates only a few of the equivalent trunks. Thus for the main group G, three of the ten equivalent trunks assigned to the third level or subgroup are shown, one of the trunks being connected to the fourth set of terminals in said subgroup. Similarly in group G', three trunks, which are the equivalent of those just mentioned, are shown as assigned to the third level or subgroup. Each trunk has a relay 1 individual thereto which may be operated in any well-known manner when the trunk is taken for use. Should one or more trunks in a subgroup in group G be idle, its corresponding relay 1 will be deenergized and a relay 2, common to the trunks of said subgroup, will be maintained energized through the contacts of the deenergized relays 1. When all the trunks in said subgroup are busy, a circuit for relay 2 will no longer be maintained since all of the relays 1 will be energized and relay 2 will, therefore, release and close a circuit through its lower contact for a similar relay 2', common to the subgroup of the trunks in group G' which are equivalent to the first-named subgroup. If a trunk in the second subgroup is idle, the circuit for relay 2' will be completed through the contact of the relay 1' individual to said idle trunk, and relay 2' will be energized. Relays 2, 2', and other similar relays each control a brush tripping rod 3 which, when its associated relay is energized, has its trips 4 in operative position, as shown in full lines in Figs. 2 and 3. It will thus be apparent that relays 2, 105 110

2', etc., operate to preselect from the various subgroups of equivalent trunks, the first subgroup in which an idle trunk is to be found.

5 Each of the selectors S and S' includes a shaft 5 carrying a number of brush sets 6 and 6' equal to the number of main groups G, G', etc. The brushes of each set are normally spaced by insulated spreaders 7, pivoted in a frame 8, and having an extension or lever 9, which contacts with a trip 4 when the latter is in its operative position, as shown in full lines in Fig. 2, as soon as the selector starts its secondary or trunk hunting movement. The spreaders 7 are thus moved from engagement with the brushes to the dotted line position shown in Fig. 2, and the brushes are permitted to engage the terminals of the subgroup of trunks in which 10 the idle trunk is located, whereupon the trunk hunting movement of the selector proceeds as usual. In order that the brushes may be restored to their normal positions upon the release of the selector, an abutment 15 10' is arranged in the path of the lever 9 and is contacted thereby as the selector is returned to normal whereby said lever is again moved to its full line position in Fig. 2 and the spreaders 7 engaged with said 20 brushes to separate the same.

It is believed that the invention will now be fully understood from the following detailed description of the operation in extending a connection. Let it be assumed that 25 a subscriber at substation A desires to extend a call and that the first digit of the desired number is 3. Let it further be assumed for the moment that there are one or more idle trunks located in the subgroup of equivalent 30 trunks terminating in the third level of the main group G, and that the first of said idle trunks is connected to the fourth set of terminals in said subgroup. In this instance the relay 1, individual to said fourth trunk, 35 and similar relays of any other idle trunks, will be deenergized. A circuit will then be established for the common relay 2 extending from grounded battery through the winding of said relay, and the contact of relay 1 of the fourth trunk to ground. Relay 2, in energizing, rotates the trip rod 3 associated therewith to move the trips 4 to operative position and at the same time opens the lower or normal contact of the relay to 40 prevent energization of the relay 2' or other similar relays. It will thus be obvious that the tripping rods 3 associated with relay 2' and the other similar relays will be prevented from being moved to their operative positions, and consequently the first subgroup of 45 equivalent trunks containing an idle one will be preselected.

Upon the removal of the receiver from the switchhook at substation A, a circuit is immediately established to operate a line finder

B or other switch of well-known construction, and upon engagement of the brushes of said switch with the terminals of the calling line, a circuit will be established for the line relay 10 of the selector S extending from 70 grounded battery through the right-hand winding of said relay, the wiper 11 in position 1, brush 12, terminal 13, substation apparatus, terminal 14, brush 15, wiper 16 in position 1, and left-hand winding of relay 75 10 to ground. Relay 10 energizes and establishes front contact a circuit for the slow-to-release relay 17, which, in turn, prepares at its front contact a circuit for the slow-to-release relay 18. The subscriber now operates his impulse sender and proceeding under the assumption that the first digit of the wanted number is 3, three impulses are transmitted. The first interruption of the circuit of line 80 relay 10, due to the first impulse transmitted, causes said relay to release its armature and establish the circuit for relay 18, which then energizes. Relays 17 and 18, being slow to release, maintain their front contacts closed during the transmission of the impulses. Energization of relay 18 establishes a circuit for escape magnet 19 through the wiper 20 in position 1, but the escape mechanism controlled by magnet 19 is so arranged that 85 the wipers thereof will not be moved into position 2 until the magnet releases. Each closure of the back contact of relay 10, in response to the impulses transmitted, establishes a circuit for the primary stepping 90 magnet 21 of the selector, extending from grounded battery through the winding of said magnet, rotary off-normal contact 22, front contact of relay 17, and the back contact of relay 10 to ground. Magnet 21 responds to each closure of the circuit therefor 95 and operates to step the shaft 5 of the selector in its primary or vertical movement. In response to the three impulses transmitted, the sets of brushes 6, 6', etc., will be moved 100 to positions opposite the third subgroups of equivalent trunks in the various corresponding main groups G, G', etc. Inasmuch as the lower or front contact of relay 2 is 105 opened, it will be apparent that the tripping rod 3, associated with the third subgroup in group G' and other similar trip rods of the other main groups, will be in normal or inoperative position so that the brush set 6' and the remaining brush sets associated with 110 the other main groups will not be affected during the secondary or hunting movement of the selector. At the end of the primary movement, the lever 9 of brush set 6 will be disposed so as to contact the adjacent trip 115 4 carried by the tripping rod 3 of group G as soon as the selector begins its trunk hunting movement. At the termination of the transmission of the impulses relay 18, after an interval, releases and opens the circuit for es- 120

125

cape magnet 19, which then releases to move its wipers into their second positions. A self-interrupting circuit for the secondary magnet 23 is then established, extending 5 from grounded battery through the winding of said magnet, contact 24, wiper 25 in position 2, and the front contact of relay 10 to ground. Magnet 23 operates to rotate the shaft 5 of the switch, and upon the first 10 step thereof in its secondary movement, the off-normal contact 22 is opened. The initial movement of the shaft causes lever 9 of brush set 6 to be rocked about its pivot and the spreaders 7 to be disengaged from the 15 brushes so that the latter will engage the terminals of the third subgroup in group G. The idle condition of a trunk is denoted by ground potential upon the test conductor thereof, and the selector will continue to rotate and pass over the terminals of busy 20 trunks until the first idle one in the subgroup is reached. At this time a circuit is established for the escape magnet 19, extending from grounded battery through the 25 winding of said magnet, wiper 20 in position 2, the lowermost brush of brush set 6, and the test terminal of the idle trunk to ground at the succeeding selector. In this instance the energization of the escape magnet over 30 the circuit just traced causes the side switch to move its wipers into position 3, whereupon the stepping circuit for the secondary magnet 23 is permanently opened and the selector comes to rest on the terminals of the 35 idle trunk. Upon the seizure of the idle trunk, the ground potential at the succeeding selector is removed in any manner well known in the art, and a circuit (not shown) is established for the relay 1 individual to 40 the seized trunk. Relay 1 energizes and opens its contact to prevent the establishment of a circuit for the magnet 2 through said contact while the trunk is being used. It will thus be seen that if all of the trunks 45 in the third subgroup are taken for use, the associated relays 1 will all be energized and a circuit will no longer be maintained for relay 2, whereupon the same will release and, in doing so, close its lower contact to 50 establish a circuit for relay 2', associated with the third subgroup in group G', should any of the individual relays assigned to said group be in normal position.

If at any time during the primary or secondary movement of the selector, a subscriber at A should replace his receiver upon the switchhook, relay 10 will immediately deenergize and open the circuit for relay 17, which, after an interval, will release. A 55 circuit will then be established for the release magnet 26, extending from grounded battery through the winding of said magnet, the off-normal contact 27, which is closed upon the first vertical step of the switch shaft 5, the side switch wiper 28 in posi-

tions 1 or 2, and the back contacts of relays 17 and 10 to ground. Magnet 26 will energize and lock up through the off-normal contact 27 and the contact 29 until the selector has been restored to normal, whereupon the off-normal contact 27 will again be opened to break the locking circuit for said magnet.

When the selector S is operated to seize the idle trunk, as above described, and the side switch wipers have been moved into their third positions, the subscriber's line will be extended through wipers 11 and 16 and the uppermost brushes of brush set 6 to the trunk leading to the next succeeding selector, which may be constructed similarly to the one shown in the drawing. Succeeding impulses transmitted from substation A will operate the succeeding selectors in a manner which will be clearly understood.

At the termination of the conversation, the selector succeeding selector S releases and again connects ground to the test conductor of the seized trunk, and at the same time opens the energizing circuit of the relay 1 individual to said trunk, which then releases. Placing of ground upon the conductor of said trunk establishes an energizing circuit for the release magnet 26 over the path previously described to the side switch wiper 28 in its third position, and from thence through the lowermost brush of the brush set 6. Magnet 26 energizes and locks up, as previously described, and the selector S is thereupon restored to normal. Upon the restoration of the selector to its normal position, lever 9 of brush set 6, which is in the operated position shown in dotted lines in Fig. 2, contacts the abutment 10' and is thereby restored to its normal position with the spreaders 7 in engagement with the intermediate brushes of the set, thus restoring said brushes to normal. The line finder B is also restored in a well-known manner and the apparatus is again ready for the extension of another call.

What is claimed is:

1. In a telephone system, a selector, a plurality of trunks terminating in said selector and arranged in equivalent subgroups, means for preselecting a subgroup containing an idle trunk, and means including said selector for operating said selector to select said idle trunk.

2. In a telephone system, a selector, a sender, groups of trunks terminating in said selector and comprising subgroups of equivalent trunks, means for preselecting a subgroup containing an idle trunk, and means including said sender for operating said selector to select said idle trunk.

3. In a telephone system, a selector, a sender, groups of trunks terminating in said selector and comprising subgroups of equivalent trunks, sets of brushes for said selector,

- the brushes of which are normally in inoperative relation to the terminals of said trunks, means for preselecting a subgroup in which an idle trunk is located, means including said sender for operating said selector, and means for actuating a set of brushes to contact the terminals of the subgroup containing the idle trunk. 65
4. In a telephone system, a selector having primary and secondary movements, a sender, groups of trunks terminating in said selector and comprising subgroups of equivalent trunks, sets of brushes for said selector, the brushes of which are normally in inoperative relation to the terminals of said trunks, means for preselecting a subgroup containing an idle trunk, means including said sender for operating said selector, and means for actuating a set of 70 brushes at the beginning of the secondary movement of said selector to contact the terminals of the subgroup containing the idle trunk. 75
5. In a telephone system, a selector, a sender, a plurality of trunks terminating in said selector and arranged in equivalent subgroups, switching means for determining the condition of the trunks in each subgroup, means controlled by said switching 80 means for preselecting a subgroup of the equivalent trunks containing an idle one, and means including said sender for operating the selector to select an idle trunk in the preselected subgroup. 85
- 35 6. In a telephone system, a selector, a sender, a plurality of trunks terminating in said selector and arranged in equivalent subgroups, switching means common to the trunks of each subgroup for determining 90 the condition of the trunks therein, means common to the trunks of each subgroup and controlled by said switching means for preselecting a subgroup containing an idle trunk, and means including said sender for operating said selector to select the idle trunk in the preselected group. 95
7. In a telephone system, a sender, a selector having primary and secondary movements, means including said sender for operating said selector, groups of trunks terminating in said selector and comprising subgroups of equivalent trunks, switching means for determining the condition of the trunks in each subgroup, means controlled 100 by said switching means for preselecting a subgroup of the equivalent trunks containing an idle one, sets of brushes for said selector normally in inoperative relation to the terminals of the trunks, and means operable at the beginning of the secondary movement of the selector for actuating a set of brushes to contact the terminals of the preselected subgroup containing the idle 105 trunk. 110
8. In a telephone system, a selector having primary and secondary movements, means including a sender for operating said selector, groups of trunks terminating in said selector and comprising subgroups of equivalent trunks, sets of brushes for said switch, the brushes of which are normally in inoperative relation to the terminals of said trunks, switching means common to the trunks of each subgroup for determining the condition of the trunks therein, means common to the trunks of each subgroup and controlled by said switching means for preselecting a subgroup containing an idle trunk, and means operable at the beginning of the secondary movement of said selector for actuating a set of said brushes to contact the terminals of the preselected subgroup containing the idle trunk. 115
9. In a machine switching telephone system, a selector, a plurality of equivalent trunks terminating in said selector in a number of levels, a brush on said selector for each level, a sender for positioning said selector with a brush opposite each of said levels, said brushes being normally in inoperative relation to the terminals of said trunks, means for giving said selector an automatic secondary movement, means actuated in the beginning of the secondary movement of the selector for rendering operative the brush of a level containing an idle trunk, and means for causing said brush to seize said idle trunk. 120
10. In a machine switching telephone exchange system, a selector, subgroups of equivalent trunks terminating therein, a brush on said selector for each subgroup, a sender for positioning the selector with its brushes at the beginning of said subgroups, means common to each subgroup for rendering operative the brush of a subgroup having an idle trunk, means for imparting an automatic secondary movement to said selector, and means for causing said brush to seize said trunk. 125
11. In a machine switching telephone exchange system, a numerical selector, a number of trunks terminating in said selector and arranged in equivalent subgroups, a brush on said selector for each subgroup, a sender for giving said selector a primary movement to set its brushes in operative relation to the desired subgroups, means thereupon automatically operated for giving said selector a secondary movement over said subgroups, means actuated in the initial part of said secondary movement for rendering operative the brush of a subgroup containing an idle trunk, and means for causing said brush to seize said trunk. 130
- In witness whereof, I hereunto subscribe my name this 16th day of April, A. D., 1920.
- CHARLES L. GOODRUM
